(57) **CLAIM**

The ornamental design for an adjustable three wheel drifting scooter, as shown and described.

DESCRIPTION

FIG. 1 is a perspective view of one embodiment of the adjustable three wheel drifting scooter showing my new design; FIG. 2 is another perspective view thereof;

FIG. 3 is a front elevation view thereof;

FIG. 4 is a back elevation view thereof;

FIG. 5 is a left elevation view thereof;

FIG. 6 is a right elevation view thereof;

FIG. 7 is an upward plan view thereof;

FIG. 8 is a downward plan view thereof;

FIG. 9 is a perspective view of the adjustable three wheel drifting scooter of FIG. 1 in an alternate configuration;

FIG. 10 is another perspective view thereof;

FIG. 11 is a front elevation view thereof;

FIG. 12 is a back elevation view thereof;

FIG. 13 is a left elevation view thereof;

FIG. 14 is a right elevation view thereof;

FIG. 15 is an upward plan view thereof; and,

FIG. 16 is a downward plan view thereof.

The broken lines represent portions of the article that form no part of the claim.
